UNITED STATES PATENT OFFICE.

T. CLARENCE HEISEY, OF NEWARK, OHIO, ASSIGNOR TO A. H. HEISEY & CO., OF NEWARK, OHIO.

DESIGN FOR A SURFACE ORNAMENTATION FOR A GOBLET OR SIMILAR ARTICLE.

Application filed May 8, 1920. Serial No. 379,984. Term of patent 14 years.

To all whom it may concern:

Be it known that I, T. CLARENCE HEISEY, a citizen of the United States, residing at Newark, county of Licking, and State of Ohio, have invented a new, original, and ornamental Design for a Surface Ornamentation for Goblets or Similar Articles, of which the following is a specification.

The drawing is a side elevation of a goblet embodying the ornamental design.

The design is characterized by a bowl having spaced upright lines, converging sub-

stantially at the bottom of the bowl and presenting the effect of a number of sides or faces for the bowl.

A surface ornamentation near the top of the bowl includes a frieze and several rows of intertwined wave lines.

I claim—

The ornamental design for surface ornamentation for a goblet or similar article, substantially as shown and described.

T. CLARENCE HEISEY.
